(57) **CLAIM**

The ornamental design for a transaction device, as shown and described.

DESCRIPTION

FIG. 1 is a front perspective view of the transaction device showing my new design;

FIG. 2 depicts a front view thereof;

FIG. 3 depicts a back view thereof;

FIG. 4 depicts a side view thereof;

FIG. 5 depicts an opposite side view thereof;

FIG. 6 depicts a bottom view thereof; and,

FIG. 7 depicts a top view thereof.

The broken lines in the drawings illustrate environmental structure on the article and form no part of the claimed design.
